UNITED STATES PATENT OFFICE.

HENNING ANDERSON, OF CHICAGO, ILLINOIS.

WIRE-TWISTING DEVICE.

1,396,013.

Specification of Letters Patent.

Patented Nov. 8, 1921.

Application filed June 26, 1920. Serial No. 391,917.

To all whom it may concern:

Be it known that I, HENNING ANDERSON, a citizen of the Kingdom of Sweden, residing at Chicago, in the county of Cook and State of Illinois, have invented certain new and useful Improvements in Wire-Twisting Devices, of which the following is a specification.

This invention relates to improvements in wire twisting devices and its object primarily is to provide means for twisting the ends of tie or binding wire to securely retain the object bound in adjusted or bound position. A further object is to provide a device of this class that is of simple construction, cheap to manufacture and durable and efficient in use. With the foregoing and other objects in view the invention consists in the combination and arrangement of parts to be hereinafter fully described, pointed out in the appended claims and illustrated in the accompanying drawings which form a part of this specification and in which—

25 Figure 1 is a vertical sectional view through the device.

Fig. 2 is a fragmentary side view of Fig. 1.

Fig. 3 is a fragmentary plan view of a 30 concrete fence showing the application of my device to bind the fence elements together.

Fig. 4 is a vertical sectional view through the fence of Fig. 3.

35 Fig. 5 is a view in elevation of Fig. 4 from the side to which the wire twister is secured.

Fig. 6 is a view of the twisted portion of the binding wire operated upon.

40 Like reference characters denote corresponding parts throughout the several views.

In Figs. 3, 4 and 5 I have shown the application of the device and I have used it to bind together the component parts of a 45 concrete fence. It is, of course, understood that the device may be used in connection with most any objects to be tied or bound together with wire, the fence being illustrated in this case only to show the application.

50 The wire twister comprises a shell body 1, preferably circular in cross section, having one open end formed with the serrations 2 and formed with the elongated slot 3, said shell being formed also with the inner annular partition 4. Snugly fitting within

the shell 1 and movable longitudinally thereof is an annular jacket 5 that carries a stop screw 6 disposed in the slot 3 of shell 1, said jacket being formed with an outwardly extending flange 7 adapted to rest upon the upper end of the shell 1 and with an inwardly extending annular shoulder 8 substantially opposite the flange 7, said shoulder 8 serving as an abutment for one end of an expansion coil spring 9 arranged within the jacket, the opposite end of said spring resting upon the shell partition 4. The spring 9 serves to yieldingly force the jacket out of the non-serrated end of the shell, said members being positively connected, however, by the screw 6.

Upon the outer end of the jacket 5 and partly upon the flange 7 thereof is a ring 10 secured to said jacket by the screws 11, 75 said ring being formed with an inwardly extending flange 12 that seats in an annular recess formed in the periphery of a rotary cap 13 that is seated upon the jacket-shoulder 8, said cap forming a closure for 80 one end of the jacket, said cap being formed with the perforation 14. The cap is formed with the integral upstanding post or stem 15 to which the block 16 is pivotally secured by the pin 17, said block being bifurcated at its pivoted end to receive the post 15, the base of the bifurcation forming a shoulder 18 adapted, when the block is turned at right angles to the post, for engagement with one side of the post. A plate 19 is formed with serrations 20 and is secured to the block 16 by the screws 21, said plate being formed centrally with a threaded perforation in alignment with a threaded groove in the block 16 to receive the screw 22 whereby the shank 23 is adjustably and removably secured to said plate and block, the base 24 of said shank being serrated and said shank, at its opposite end, being provided with the handle 25.

100 When a strand of wire 26 is to be twisted upon itself or two strands of wire to be twisted together the operation is as follows: The wire is first placed about the object to be bound and the ends passed through the shell 1, through the perforation 14 in cap 13 and then placed opposite each other between the base 24 of the shank 23 and the plate 19. The shank is now tightened down upon the wire. In the case of the concrete fence 105 shown in Figs. 3, 4 and 5 the wire is passed around the fence post 27, through the rail

28, around the spacer block 29, through rail 30, about post 31 and then back and its ends located as previously described. This concrete fence is formed of two parallel rails 5 28 and 30 spaced apart by the spacer blocks 29. The fence posts 27 and 31 are placed outside the rails 28, 30 with relation to the block 29 and in alinement therewith and the members 27, 29, 31 and the rails are secured 10 together with the binding wire by means of my twisting device. The space between the fence rails 28, 30 and between successive spacer blocks 29 is filled in with concrete. With the ends of the wire to be twisted in 15 position the serrated end of the shell 1 rests upon the object being bound. The shank 23, plate 19, block 16, post 15 and cap 13 are now rotated by means of the handle 25 when that portion of the wire strands between the 20 cap and the object being bound will be twisted as shown in Fig. 6. The spring 9 in the jacket 5 forcing the members 1, 5 apart serves to stretch the wire and prevent it from being knotted while being twisted. 25 When the wire is twisted and the object held thereby securely bound the shank 23 is loosened from the plate 19 and the wire ends freed.

What is claimed is:—

- 30 1. In a wire twister, a shell body, a jacket slidably secured to said shell body, means for yieldingly urging said shell and jacket out of mutual engagement, means for limiting the relative movement of said shell body 35 and jacket, a rotary cap carried by said jacket, a stem for said cap, and adjustable wire-engaging members carried by said stem. 40 2. In a wire twister, a shell body, a jacket slidably secured to said shell body, means for yieldingly urging said shell and jacket out

of mutual engagement, means for limiting the relative movement of said shell and jacket, a rotary cap carried by said jacket, a stem for said cap, and adjustable wire-engaging members carried by said stem, said 45 members including a bifurcated block pivotally secured to said stem.

3. In a wire twister, a shell body, a jacket slidably secured to said shell body, an expansion coil spring connecting said shell 50 body and jacket, means for limiting the movement of said jacket longitudinally of said shell body, a rotary cap carried by said jacket and formed with a wire-receiving perforation, a stem for said cap, and adjustable wire-engaging members carried by said stem, said members including a bifurcated 55 block pivotally secured to said stem.

4. In a wire twister, a terminally serrated shell body formed with an elongated slot, a jacket slidably secured to said shell body, an expansion coil spring connecting said shell body and jacket, a screw carried by said jacket and disposed in the slot in said shell body, a rotary cap carried by said jacket and 60 formed with a wire-receiving perforation, a stem for said cap, a bifurcated block pivotally connected to said stem, a serrated plate carried by said block, a shank screw-connected to said plate and block to bind the 70 wire against the former member, and a handle for said shank.

In testimony that I claim the foregoing as my own I have hereto affixed my signature in the presence of two subscribing witnesses. 75

HENNING ANDERSON.
